CONTROLLING DEVICE FOR LIQUID
DISPENSING APPARATUS

Einar M. Orbeck, Norristown, Pa., assignor to
John Wood Manufacturing Company, Inc.,
Conshohocken, Pa., a corporation of Delaware

Application May 27, 1937, Serial No. 145,055

7 Claims. (Cl. 221—95)

My invention is generally applicable to metering pumps for dispensing gasoline, for instance, of the character disclosed in Letters Patent of the United States No. 2,022,629 granted November 26, 1935 to Joseph C. Woodford as assignor to 5 John Wood Manufacturing Company, Inc., and No. 2,062,997 granted December 1, 1936 to me as assignor to the same corporation. The present invention is also applicable to the apparatus shown in my copending application Serial No. 10 145,056, filed May 27, 1937 for Letters Patent of the United States and assigned to said corporation.

It is characteristic of both forms of metering pumps, respectively disclosed in said Letters Patent, that the liquid to be dispensed is drawn from a subjacent tank and discharged through a flexible dispensing hose by means of a pump actuated by an electric motor, and that said 15 motor is controlled by an electric switch operable by a vertically reciprocatory operating bar which is connected with a hook lever projecting exterior to the pump casing and adapted to support the dispensing hose in idle position; so that 20 when the hose is hung on said hook lever the switch is opened and the pump stopped, and when the hose is removed from said lever the latter may be manipulated to close the switch to energize the pump. Moreover, as disclosed in each 25 of said Letters Patent, and application, the electrically driven pump forces the liquid through a meter including a rotor which is connected to drive a registering mechanism indicating the volume of liquid dispensed and, in said Letters Patent No. 2,062,997, and said application, the registering mechanism not only indicates the 30 volume of liquid dispensed, but also computes and registers the value thereof. The form of my invention disclosed in said application, wherein the vertically reciprocatory operating bar aforesaid is utilized to initiate the operation of the computing registering mechanism, simultaneously 35 with the closure of the electric switch for operating the pump, is now being manufactured by said corporation in conjunction with the apparatus shown in said Woodford patent. Consequently, it is highly important in the several forms of apparatus aforesaid to insure that the vertically reciprocatory operating bar shall be 40 properly actuated to the desired extent for effecting its double function aforesaid.

Therefore, the purpose and effect of my present invention is to insure the proper actuation of said vertically reciprocatory operating bar by 45 mechanical means which supplement the initial 50

manual movement of such bar by the operator. As hereinafter described, such means includes a spring pressed toggle lever linkage.

My invention includes the various novel features of construction and arrangement herein- 5 after more definitely specified.

In said drawings: Fig. I is a fragmentary plan view, and Fig. II a fragmentary vertical sectional view, of apparatus of the type disclosed in said Woodford patent, but including a convenient embodiment of my present invention. 10

Fig. III is a fragmentary plan view, and Fig. IV a fragmentary vertical sectional view, of apparatus of the type disclosed in my Letters Patent and pending application aforesaid, but including 15 a convenient embodiment of my present invention.

Fig. V is an elevation of a metering pump of the curbstand type, conveniently embodying my 20 invention.

Referring to Figs. I, II and V; the pump housing 1, which is a rectangular tubular vertically extending casing, has the hook lever 2 fulcrumed on the pivot 3 in the bracket 4 and is operatively connected with the vertically reciprocatory operating bar 5 as above mentioned. The connecting means, best shown in Figs. I and II includes the link 6 which has its upper end 6' extending through the inner end of said hook lever 2, and has its lower end 6'' extending through the pair of similar parallel levers 7 which are both fulcrumed on the pivot pin 8 supported in the bracket 9 which is rigidly connected with said housing 1. The right hand ends of said levers 7 are rigidly connected by the cross bar 35 7' from which the pair of similar springs 11 extend to the cross bar 12 which is rigidly mounted in the left hand end of the single lever 13 which is fulcrumed at its right hand end on the pivot pin 14 which is journaled in the pendent right 40 hand end 9' of said bracket 9. Said single lever 13 is connected by the pivot pin 13' with the lower end of the link 15, the upper end 15' of which is pivotally connected with said vertically reciprocatory operating bar 5. Said single lever 45 13 is also connected by the pivot pin 16 with the upper clevis end of the bolt 17 which is vertically adjustable, secured in the bracket 18 which is rigidly connected with the motor switch rod 19, conveniently by the set screws 20, as indicated 50 in Fig. II. Said rod 19 is mounted for reciprocation in suitable bearings in said housing 1 including the bearing bracket 1' which is rigidly secured to said housing. As shown in Fig. V; said rod 19 has rigidly connected therewith the bracket 19' 55

which is operatively connected with the switch 19". The effect of the arrangement above described is that when the outer end of said hook lever 2 is depressed, by the weight of the dispensing hose or otherwise, toward the position shown in Fig. II, said operating bar 5 and switch rod 19 are both uplifted to the extreme limit of their movement by the snap action of said springs 11 upon the toggle lever linkage described and are upheld in that position, in which the computing registering mechanism and the motor switch are inoperative and the motor idle, unless and until the indicating means a^1 and a^2 of the computing registering mechanism A are reset to their zero position. That zeroizing operation may be effected by the operator manually turning the setback shaft 21 by means of the crank handle 22 shown in Fig. I.

Said indicating means a manifests the price 20 per gallon of the liquid dispensed, said indicating means a^1 indicate the gallons and fractions of a gallon dispensed, and said indicating means a^2 indicate the value of the quantity of liquid dispensed at the price displayed. As indicated 25 in Fig. V; the computing registering mechanism A is arranged to be actuated by the shaft b of a rotor in the meter B which is turned one revolution for each gallon of liquid passed through the meter. Said rotor is turned by liquid which is 30 uplifted from a subjacent tank through the conduit C by the pump D which is connected by the belt E with the electric motor F which supports the electric switch box G. The liquid is delivered from said pump D through the conduit H, air 35 eliminator I and conduit J into the casing of the meter B, and passes from the meter casing through the conduit K and sight gage L to the dispensing hose M having the nozzle N arranged to be supported by said hook lever 2.

40 If and when the indicating means aforesaid are at their zero position; the operator may initiate the next succeeding dispensing operation by pulling the chain 23. The consequent downward movement of the inner end of said hook lever 2 and the link 6 swings the right hand end of the pair of levers 7 downward and, when such downward movement has swung the right hand ends of the springs 11 down below a line drawn through the axes of the pivot pins 12 and 14, said springs 11 snap the pair of links 13 downward to the lower limit of their movement and of the movement of the operating bar 5 of the registering mechanism and said springs then hold the mechanism in that position for a dispensing 50 operation until the hook lever 2 is again depressed at its outer left hand end toward the position shown in Fig. II.

As above stated, part of the mechanism shown in Figs. I and II is of the character disclosed in 60 the Woodford patent aforesaid and that part includes the chain 23 which extends between the pair of guide rollers 24, shown in Fig. I, and is connected at its inner end with the pivot pin 25 at the lower end of the bell crank lever 26. Said lever 26 is fulcrumed on the pivot pin 27 in the bracket 28 fixed in said housing 1, and the upper end of said lever 26 overhangs the plunger 29 which is mounted to reciprocate vertically in the flange 30 on said bracket 28. Said plunger 29 is 65 rigidly connected with said bracket 28 fixed upon the switch operating rod 49, as above described; so that the effect of pulling said chain is to push down said rod 49 and thereby close the electric switch to energize the pump motor and supply 70 the dispensing hose with liquid to be dispensed.

However, as above stated, such dispensing operation cannot be effected unless and until the indicating mechanism connected with the operating bar 5 is placed at its zero position and the release of said bar 5 for downward movement thus 5 effected. In other words; it is impossible to operate said switch rod 19 by said chain 23 until the means a^1 indicating the volume of liquid dispensed has been set at its initial zero position preceding any dispensation of liquid.

10 Referring to Figs. III and IV; the pump housing 31, which is a rectangular tubular vertically extending casing, has the hook lever 32 fulcrumed on the pivot 33 in the bracket 34 and operatively connected with the vertically reciprocating operating bar 35 like said bar 5. The connecting means includes the link 36 which has its upper end 36' extending through the inner end of said hook lever 32 and has its lower end 36" extending through the pair of similar parallel levers 37 which are both fulcrumed on the pivot pin 38 supported in the bracket 39 which is rigidly connected with said housing 31. The right hand ends of said levers 37 are rigidly connected by the cross bar 37' from which the pair of similar 20 springs 41 extend to the cross bar 42 which is rigidly mounted in the left hand end of the single lever 43 which is fulcrumed at its right hand end on the pivot pin 44 which is journaled in the pendent right hand end 39' of said bracket 39. 30 Said single lever 43 is connected by the pivot pin 43' with the lower end of the link 45, the upper end 45' of which is pivotally connected with said vertically reciprocating bar 35. Said single lever 43 is also connected by the pivot pin 35 46 with the upper clevis end of the bolt 47 which is vertically adjustable in the head 47' of the pivot 47" which is pivotally connected with the bracket 48 which is rigidly connected with the motor switch rod 49. Said rod 49 is mounted 40 for reciprocation in suitable bearings in said housing 31 including the bearing bracket 31' which is rigidly secured to said housing.

The effect of the arrangement above described is that when the outer end of said hook lever 32 is depressed, by the weight of the dispensing hose or otherwise, toward the position shown in Fig. IV, said operating bar 35 and switch rod 49 are both uplifted to the extreme limit of their movement by the snap action of said springs 41 upon the toggle lever linkage described, and are upheld in that position, in which the computing registering mechanism and the motor switch are inoperative and the motor idle, unless and until the indicating means of the computing registering mechanism are reset to their zero position. That zeroizing operation may be effected by the operator manually turning the setback shaft 51 by means of the crank handle 52, shown in Fig. III.

55 If and when the indicating means aforesaid are at their zero position; the operator may initiate the next succeeding dispensing operation by uplifting the outer end of said hose supporting hook lever 32. The consequent downward movement of the inner end of said hook lever 32 and the link 36 swings the right hand end of the pair of levers 37 downward and, when such downward movement has swung the right hand ends of the springs 41 down below a line drawn through the axes of the pivot pins 42 and 44, said springs 41 snap the single lever 43 downward to the lower limit of its movement and of the movement of the operating bar 35 of the registering mechanism, and the operating rod 49 of the motor controlling switch; and said springs then hold the 70 75

mechanism in that position for a dispensing operation until the hook lever 32 is again depressed at its outer left hand end toward the position shown in Fig. IV. However, as above stated, such dispensing operation cannot be effected unless and until the indicating mechanism connected with the operating bar 35 is placed at its zero position and the release of said bar 35 for downward movement thus effected. 5
10 In other words; it is impossible to operate said switch rod 49' which is operatively connected with said switch 19'' like said rod 19 above described, until the means indicating the volume of liquid dispensed has been set at its initial zero 15 position preceding any dispensing of liquid.

It is characteristic of both forms of my invention chosen for illustration that a spring pressed toggle lever linkage insures the proper actuation of both the vertically reciprocatory operating bar 20 of the computing registering mechanism and the vertically reciprocatory operating bar of the electric switch controlling the motor of the pump by which liquid is dispensed.

Therefore, I do not desire to limit myself to the 25 precise details of construction or arrangement or method of operation herein set forth as it is obvious that various modifications may be made therein without departing from the essential features of my invention as defined in the appended 30 claims.

I claim:

1. In liquid dispensing apparatus, the combination with a pump for the liquid to be dispensed, actuated by an electric motor; of an electric 35 switch controlling said motor; a reciprocatory rod for operating said switch; a spring pressed toggle lever linkage operatively connected with said reciprocatory rod; and a manually movable lever connected for initiating movement of said 40 rod; whereby upon initiation of reciprocatory movement of said rod by manipulation of said lever, said spring pressed toggle lever linkage effects complete movement of said rod in the direction of movement thus manually initiated, 45 and thus insures proper placement of said rod in either direction for respectively initiating and terminating each dispensing operation.

2. In liquid dispensing apparatus, the combination with a pump for the liquid to be dispensed, 50 actuated by an electric motor; of an electric switch for controlling said motor; a reciprocatory rod for operating said switch; a spring stressed lever linkage connected to said rod; and a manually movable lever connected for initiation of 55 movement of said linkage; whereby upon initiation of movement of said linkage by operation of said manually movable lever said linkage automatically effects complete movement of said rod in either direction of movement of said rod thus 60 manually initiated, and thus insures proper movement of said switch in either direction for respectively initiating and terminating each dispensing operation.

3. In liquid dispensing apparatus, the combination with a pump for the liquid to be dispensed, actuated by an electric motor; of an electric 65 switch for controlling said motor; a reciprocatory rod for operating said switch; a spring stressed lever linkage connected to said rod; a flexible hose through which the liquid is dispensed from said pump; and a pull chain and lever for connecting said hose with said rod; whereby upon initiation of movement of said rod by movement of said hose, chain and lever, said 70 linkage effects complete movement of said rod in

either direction of movement of said rod thus manually initiated, and thus insures proper movement of said switch in either direction for respectively initiating and terminating each dispensing operation. 75

4. In liquid dispensing apparatus, the combination with a pump for the liquid to be dispensed, actuated by an electric motor; of an electric switch for controlling said motor; a reciprocatory rod for operating said switch; a spring stressed 10 toggle lever linkage connected to said rod; and a manually movable lever connected for initiation of movement of said linkage; whereby upon initiation of movement of said linkage by operation of said manually movable lever said linkage 15 automatically effects complete movement of said rod in either direction of movement of said rod thus manually initiated, and thus insures proper movement of said switch in either direction for respectively initiating and terminating each dispensing operation. 20

5. In liquid dispensing apparatus, the combination with a pump for the liquid to be dispensed, actuated by an electric motor; of an electric switch for controlling said motor; a reciprocatory 25 rod for operating said switch; a spring stressed toggle lever linkage connected to said rod; a flexible hose through which the liquid is dispensed from said pump; and a pull chain and lever for connecting said hose with said rod; 30 whereby upon initiation of movement of said rod by movement of said hose, chain and lever, said linkage effects complete movement of said rod in either direction of movement of said rod thus manually initiated, and thus insures proper 35 movement of said switch in either direction for respectively initiating and terminating each dispensing operation.

6. In liquid dispensing apparatus, the combination with a pump for the liquid to be dispensed, 40 actuated by an electric motor; of an electric switch for controlling said motor; a reciprocatory rod for operating said switch; a spring stressed lever linkage connected to said rod; and a manually movable lever arranged to support a dispensing hose connected with said pump, and connected for initiation of movement of said linkage; whereby upon initiation of movement of said linkage by operation of said manually movable lever said linkage automatically effects complete movement of said rod in either direction of movement of said rod thus manually initiated, 45 and thus insures proper movement of said switch in either direction for respectively initiating and terminating each dispensing operation. 50

7. In liquid dispensing apparatus, the combination with a pump for the liquid to be dispensed, actuated by an electric motor; of an electric switch for controlling said motor; a reciprocatory rod for operating said switch; a spring stressed 60 lever linkage connected to said rod; a manually movable lever arranged to support a dispensing hose connected with said pump, and connected for initiation of movement of said linkage; and a pull chain and lever for connecting said hose 65 with said rod; whereby upon initiation of movement of said rod by said hose supporting lever or by said hose, chain and lever, said linkage effects complete movement of said rod in either direction of movement of said rod thus manually 70 initiated, and thus insures proper movement of said switch in either direction for respectively initiating and terminating each dispensing operation.
